(No Model.)

P. F. WELLS.
CULTIVATOR.

No. 601,295.

Patented Mar. 29, 1898.

UNITED STATES PATENT OFFICE.

PHILIP F. WELLS, OF MILFORD, MICHIGAN.

CULTIVATOR.

SPECIFICATION forming part of Letters Patent No. 601,295, dated March 29, 1898.

Application filed January 22, 1897. Serial No. 620,215. (No model.)

To all whom it may concern:

Be it known that I, PHILIP F. WELLS, a citizen of the United States, residing at Milford, county of Oakland, State of Michigan, have 5 invented a certain new and useful Improvement in Cultivators; and I declare the following to be a full, clear, and exact description of the invention, such as will enable others skilled in the art to which it appertains to 10 make and use the same, reference being had to the accompanying drawings, which form a part of this specification.

My invention has for its object certain new and useful improvements in cultivators; and 15 it consists of the construction, combination, and arrangement of devices hereinafter described and claimed, and illustrated in the accompanying drawings, in which—

Figure 1 is a view in perspective embodying my invention. Fig. 2 is a detail view of one of the draw-bars, showing also the manner of attaching the spring thereto and to the lifting-bracket. Fig. 3 is a section through the bar A', one of the rings A³, and a portion 25 of the adjacent casting A².

My invention is designed to secure an efficient equalization of the draft and to provide means for holding the cultivator-sections in desired position.

30 My invention also embraces the general construction and arrangement which I will proceed more fully to describe.

A A represent pendent portions of an arched axle, the upper extremities of which have an 35 adjustable and swinging engagement with a bar A' intermediate the portions A A, said bar running essentially at right angles to the pole or tongue B and upon which the rear end of the pole or tongue is secured in any 40 suitable manner, as indicated at B'.

C C represent two cultivator-sections.

D D represent two draw-bars, through the rear ends of which the axle is sleeved, as at a. These draw-bars are each made of an arm d, 45 running forward from the axle at an upward inclination a desired distance, the front portions of said draw-bars being each constructed with an upwardly-projecting arm d', integrally united to the arms d, the two arms forming 50 a solid draw-bar. The arms d' of the draw-bars are carried upward, being bent so as to stand nearly perpendicular to an evener E,

attached to the tongue, to which their upper ends are secured. The draw-bars are each formed without a joint at the bend uniting 55 the arms d and d'. It will be seen that the draw-bars are thus carried upward to substantially a level with the tongue, the evener E being secured, preferably, to the under side of the tongue, as shown. The carrying of the 60 draw-bars thus up to substantially a level with the tongue and making them in a single integral unjointed piece is believed to be novel. A strap F passes over the tongue and is engaged at its extremities to the extremities of the evener E. 65

G indicates a yoke jointedly connected intermediate its ends to the tongue B, as indicated at g, the yoke having two depending arms g' and g².

70 Hand H' denote two draft-levers fulcrumed intermediate their ends, respectively, to a bracket h, engaged with the corresponding arm d' of the corresponding draw-bar D, as indicated at h'. To the lower ends of the 75 draft-levers H H' are engaged the whiffletrees J J'. The upper extremities of the draft-levers H H' are pivotally connected to the corresponding arms of the yoke G, as indicated at h². The yoke G is provided with suitable 80 braces g³. The lower ends of the draft-levers H H' are made longer below the fulcrum than the opposite ends, and it will be apparent that a horse attached to one of the whiffletrees may move forward the lower end of the 85 corresponding draft-lever several inches with but a slight consequent movement of the machine, so that should a horse move forward, say, some ten or twelve inches, while the other horse fell back or shirked, there would 90 be but a slight movement of the machine before the draft upon the other whiffletree would be effective, and the draft would be thereby efficiently equalized.

95 K K denote springs connected at their forward ends to the corresponding draw-bars D D, their rear extremities being adjustably connected with couplings C', attached to castings L, sleeved upon the axle, and to the front portions of the sections C C. Said couplings 100 are preferably constructed with a series of holes c, with which the rear extremities of the springs may be adjustably engaged. The springs K K are connected to the draft-bars D

by means of arms M, through the rear extremities of which the end of the corresponding portion of the axle is sleeved. The draw-bars D are constructed with elongated slots 5 d^2 , through which the forward end of the corresponding arm M is engaged, said arm being bent toward the draw-bar at its forward end and is secured in the corresponding slot by means of a nut m.

10 It will be apparent that when the sections C C are in the ground, being depressed, the draft is almost in line and, practically, does not lift at all. In fact, when the rear end of the spring is engaged in the lower hole of 15 the corresponding couplings C' the draft holds the sections in the ground instead of lifting; but when the sections are raised a little the line of draft begins to get above the level of the axle and of course lifts hard 20 enough to hold the sections up if the springs are of proper tension. By the raising of the sections the leverage is thus increased, so that the springs will ultimately hold the sections up. The construction of the draw-bars 25 D D with the elongated slot d^2 is for the purpose of allowing the angle of the sections to change.

The upper ends of the axle portions A A are provided with castings A² to sleeve over 30 the ends of the bar A', a set-screw a' being provided to hold each casting in a given position of lateral adjustment upon said bar. The sections C C, connected with the axle portions A A, may thus be laterally adjusted as 35 may be desired. Within the castings A² are rings A³, through which the set-screws are engaged, so that the rings will be held solid while the castings may swing freely thereupon, the castings being prevented from moving laterally.

40 As the sections are spread apart or closed together, the axles must always be kept parallel to the bar A'. Accordingly as the sections move in or out provision must be made for a yielding movement of the arms M in engagement with the draw-bars D. The provision of the slots d^2 provides for this yielding movement.

45 The sections C C are preferably constructed with two converging carrying-bars C³, engaging with the corresponding couplings C', upon which bars C³ are adjustably engaged 50 blocks C⁴, to which the spring-teeth C⁵ are attached. I preferably locate on each bar C³

two of the movable or adjustable blocks C⁴, 55 the spring-teeth connected with each being of a length permitting the shovels or blades C⁵ being either adjusted in line or in zigzag form, as may be required.

What I claim as my invention is—

60 1. In a cultivator, the combination of an axle, the slotted draw-bars, the cultivator-sections, the arms M having their forward extremities engaged in the slots of the draw-bars and their rear extremities engaged with 65 the axle, lifting-brackets engaged with the front portions of the cultivator-sections and with the axle, and springs connecting said brackets with the forward extremities of said arms, substantially as set forth.

70 2. In a cultivator, the combination of an axle, the slotted draw-bars, the cultivator-sections, the arms M having their forward extremities engaged in the slots of the draw-bars and their rear extremities engaged with 75 the axle, couplings engaged with the front portions of the cultivator-sections and with the axle, and springs connecting said couplings with the forward extremities of said arms, said springs adjustably connected with 80 said couplings, substantially as set forth.

75 3. In a cultivator, the combination of an axle, a tongue, an evener secured to the tongue, the rigid draw-bars formed with forwardly-projecting arms d and upwardly-projecting arms d', said arms d' projecting upward substantially to a level with the tongue and engaged with the evener, springs connecting the cultivator-sections with the draw-bars, a yoke jointedly connected to the tongue, and 90 draft-levers pivotally connected to the yoke, said draft-levers connected intermediate their ends with the corresponding draw-bars, substantially as set forth.

95 4. In a cultivator, the combination of an axle, the tongue, the evener, the draft-bars, the yoke depending from the tongue, the brackets and the draft-levers jointedly connected with the extremities of the yoke and having a fulcrumed connection with said 100 brackets, substantially as set forth.

In testimony whereof I sign this specification in the presence of two witnesses.

PHILIP F. WELLS.

Witnesses:

DENNIS BOYLE,
P. C. SLAUGHTER.
